UNITED STATES PATENT OFFICE.

WILLIAM D. PIERSON, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

LUBRICATING SYSTEM FOR WIRE-DRAWING MACHINES.

Application filed July 1, 1921. Serial No. 481,832.

To all whom it may concern:

Be it known that I, WILLIAM D. PIERSON, a citizen of the United States, residing at Waterbury, in the county of New Haven 5 and State of Connecticut, have invented certain new and useful Improvements in Lubricating Systems for Wire-Drawing Machines, of which the following is a specification, reference being had therein to the 10 accompanying drawings.

This invention relates to a new and useful oiling system for wire drawing machines and has for its object, among other things, to provide a system whereby all of the bearings and several gears may be kept constantly provided with a lubricant, which may be used over and over again and obtained either from a supply exterior to the machine or from a suitable reservoir connected with the machine and into which the lubricant drains after being used.

To these and other ends, my invention consists in the new and improved oiling system for wire drawing machines having certain details of construction and combinations of parts as will be hereinafter described and more particularly pointed out in the claims.

Referring to the drawings in which like 30 numerals of reference designate like parts in the several figures,—

Figure 1 is a sectional plan view of an improved wire drawing machine of the conventional type having my improved oiling 35 system connected therewith;

Figure 2 is a front elevation thereof; and Figure 3 is a similar cross-sectional view.

In a wire drawing machine where there are many wire drawing drums and a block, 40 each of which is mounted on a shaft and operated with beveled gears, it has heretofore been a difficult task to keep all of the journals and gears sufficiently lubricated, with the consequent disastrous result that the 45 work is improperly done and the parts subjected to undue wear. To, therefore, overcome this difficulty, I provide means for oiling the gears and to feed oil to all of the bearings. This is accomplished by a system 50 whereby the lubricant or oil may be originally drawn from a source of supply outside of the machine by the same pump that operates the oiling system of the machine and when sufficient oil has been thus

obtained shut off this source of supply. 55 Thereafter the oil after it has passed over the bearings and beveled gears is used until by evaporation or other means this supply has been exhausted. In connection therewith I have designed means whereby 60 the system for oiling the journals is separate and distinct from that for oiling the beveled gears and one can be in operation while the other is not or both can be operated at the same time as may be desired. 65

In the drawings which show a single unit of a wire drawing machine of the conventional type, 10 is the base plate which is modified, however, from the usual form by forming a reservoir 13 therein by the walls 70 11 and 12, the latter being upon an incline so that the oil will flow toward that portion of the reservoir 13 having the strainer 14 therein.

Supported above the base plate by the 75 standards 15 is a table 16. The main driving shaft 17 is journaled in suitable bearings 18 and fixed thereon are the bevel pinions 19 that mesh into and drive the bevel gears 20 upon the lower end of the 80 vertical shaft 21 that is journaled in the bearings 22 and 23 and has a drum 24 fixed to the upper end thereof.

All of the mechanism below the table 16 is inclosed, suitable cover plates 25 and 26 85 being provided for this purpose, these being so designed as to be readily attached or detached and having such covered openings therethrough as may seem desirable.

All of the mechanism above described, except the provision of a reservoir in the base-plate and the inclosing of the mechanism by the cover plates 25 and 26, is old and well known in the art.

A rotary oil pump 27 of any preferred 95 construction driven from the shaft 17 by a belt 28 connecting the pulley 29 on said shaft with a pulley 30 connected with the pump, draws in and forces the oil through my improved system. A four-way valve 31 having 100 a handle 33 is connected with the pump through suitable pipe connections 32 and with the strainer 14 through the pipe connection 37. A two-way valve 34 having a handle 51 is connected with the valve 31 by the pipe connection 35 with a supply tank or other exterior source and directly with the main supply pipe 38 having therein 105

the valves 39 and 40. Connected with the valve 39 is the gear feed pipe 41 and with the valve 40 the bearing feed pipe 42. As the principal supply of oil passes through 5 the main supply pipe 38, manipulation of the valve 39 either opens or closes the pipe 41 for admission of oil to the gears, and likewise by manipulation of the valve 40 the supply of oil to the bearing feed line. Thus 10 one line may be supplied with oil while the other is entirely shut off and the volume of oil to both may be equally controlled.

Connected with the gear feed pipe 41 is a jet pipe 43 having a valve 44 therein 15 which projects from the pipe 41 and terminates adjacent to the meeting face of the pinion 19 and gear 20 so that when the valve 44 is open, the oil under pressure is squirted into the teeth of both the pinion 20 and gear.

The bearings 18 are supplied with oil from the pipe 45 leading from pipe 42 and having a suitable valve 46 therein. The bearing 23 of the vertical shaft 21 is supplied with oil under pressure through the pipe 47 connected with the pipe 42 and having a suitable valve 48 therein, and the bearing 22 is similarly supplied with oil through the pipe 49 having a valve 50 therein.

30 The original source of oil supply is obtained through the pipe 36 at which time the handle 33 of the valve 31 and the handle 51 of the valve 34 are in the positions shown by full lines in Figure 1 and the valves 39 and 40 are both closed. After a sufficient supply has been thus obtained, the handles 33 and 51 are moved to the broken line positions in Figure 1 and the valves 39 and 40 are opened and a continuous supply of oil is 35 then brought to the pipes 41 and 42 from which the gears and bearings are suitably supplied by the piping as above described.

The oil after passing over the gears and bearings, drops therefrom into the reservoir 45 13 and passes through the strainer pump and the piping system as above described.

To remove all of the oil from the machine, either to clean or repair the mechanism, the handle 51 of the valve 34 is moved to the 50 broken line position in Figure 1 and the handle 33 of the valve 31 remains in its full line position, at which time the oil is withdrawn from the reservoir and forced through the valve 34 and pipe 36 to the 55 original source of supply.

Minor changes and alterations may be made within my invention, aside from those herein suggested, and I would therefore

have it understood that I do not limit myself to the exact construction herein shown and described, but claim all that falls fairly within the spirit and scope of the appended claims.

What I claim as new and desire to secure by Letters Patent, is:

1. In a wire drawing machine, a base plate having a reservoir therein; a table supported above said base plate; cover plates between said base plate and table; a pump; a connection between said reservoir and pump; a connection between said pump and each of the journals of the machine; another connection between said pump and each pair of gears of said machine, the said journal connections being separate and independent from the gear connection. 70

2. In a wire drawing machine, a base plate having a reservoir therein; a table supported above said base plate; cover plates between said base plate and table; a pump; a connection between said reservoir and pump; a connection between said pump and each of the journals of the machine; another connection between said pump and each pair of gears of said machine, the said journal connection being separate and independent from the gear connections; and a valve between said pump and connections whereby oil may be delivered to each of said connections through said pump from an exterior 90 source of supply or from said reservoir. 80

3. In a wire drawing machine, a base plate having a reservoir therein; a table supported above said base plate; cover plates between said base plate and table; a pump; a connection between said reservoir and pump; a connection between said pump and each of the journals of the machine; another connection between said pump and each pair of gears of said machine, the said 95 journal connection being separate and independent from the gear connections; a valve between said pump and connections whereby oil may be delivered to each of said connections through said pump from an exterior 100 source of supply or from said reservoir; and valve connections whereby the oil from said pump to the journal and gear connections may be entirely shut off and the oil from said reservoir withdrawn therefrom 110 and delivered through said pump outside of the machine.

In testimony whereof, I have hereunto affixed my signature.

WILLIAM D. PIERSON.
